RICHARD TIDDY GOULD, OF NEWCASTLE, IRELAND.

CHART-RULE.

1,124,421.

Specification of Letters Patent. Patented Jan. 12, 1915.

Application filed July 17, 1913. Serial No. 779,607.

To all whom it may concern:

Be it known that I, RICHARD TIDDY GOULD, a subject of the King of England, and resident of Newcastle, county Down, Ireland, 5 have invented an Improved Chart-Rule, of which the following is a specification.

The object of the present invention is an improved rule with graduated compass cards and sectors for rapidly ascertaining latitude, 10 longitude, bearings, and distances on charts and distances and bearings in surveying work et cetera.

The invention will be described in the following form which is given by way of example.

In the accompanying drawings:—Figure 1 is an elevation; Fig. 2 is a longitudinal section, and Fig. 3 a plan; Fig. 4 is a plan of the bedplate; Fig. 5 is a detail of part of 20 the apparatus; Fig. 6 is a cross section, on a larger scale, of the right hand end of the bed-plate; Fig. 7 is a cross section, also on a larger scale, of the rule at zero line showing mountings thereon.

25 In the form described there is a bedplate A' of wood or metal or other suitable material, which may conveniently be about twelve inches long, $2\frac{1}{2}$ inches wide and three-sixteenths of an inch thick. There is a slot 30 X at the right end of the base piece in the center which engages with a stationary pin X' in the bottom of the rule B in such a manner that the edges of the bedplate A' and the rule then form one continuous line 35 on either side. This bedplate has a dove-tailed recess a'' within which is slidably mounted a vertically disposed tube A. At the left hand end of the bedplate there are extensions a and b perfectly in plane therewith, and there is also a slot c nearly the 40 whole length thereof with parallel sides for purposes of observation. The rule B revolves around the tube A and on the same tube above the rule are placed two compass 45 cards A² and A³. These cards are of different diameters say 3 and 4 inches, and one is marked for true bearings and the other for magnetic bearings. They are carried upon different tubes, the inner one being designated 50 by A⁴ and fixed by slots and struts (not shown) in the carrying tube A, while the outer one marked with A⁵ revolves around the inner one and is adapted to be set by means of a set screw A⁶ to any degree 55 for variation.

On the rule B and slidably mounted in

parallel dove tailed recesses B⁰ and B^t, Fig. 5, are interchangeable slides B¹ and two racks B^{2a} and B^{2b} respectively. The said slides B¹ have prepared surfaces so that any scale may 60 be marked thereon by pen or pencil and made erasable; or the slides can be replaced by any number of the same dimensions which may be required for any number of scales on charts, plans and the like. The inner set of dove tailed recesses serve for the reception of the said racks B^{2a} and B^{2b}, provision being hereby made, on the left hand end of the rack B^{2a}, of an indicator b whose toes b b are hinged and extend downward 65 over the whole depth of the rule B. A stud b¹ is moreover mounted on each of said toes in order to facilitate the lifting of same and to permit of the rule B to be rotated over the surface of the bedplate A'. On the 70 right hand end of the rack B^{2b} is an indicator b similar to that on the rack B^{2a} except that the toes b b¹ are fixed and therefore require no stud as at b¹.

Longitudinally centered on the rule B, 80 between the edge of the disk or compass card A² and the right hand end of rule B, and where the line Z cuts said center, a bushing C, Fig. 7, is inserted. The said line Z crosses the surface of rule B transversely 85 and is continued down the edges of the rule B and marks "zero" on the surface and edges of said rule B. The pinion B^{2c} perfectly in plane with the racks B^{2a} and B^{2b}, is, by the lower portion of its spindle B³, 90 rotatably mounted between the racks and in the bushing C and is kept in position by a pin X² penetrating the spindle B³ beneath the rule B. Provision is further made of a plate B⁴ which is rotatably mounted on the central portion of the spindle B³, the pivoted end of this plate B⁴ being in the form of a semi-circle of which each quadrant is graduated from 0 to 90 degrees. At the outer end of the plate B⁴ and at the center 95 of the semi-circle is a pivot 7 on which is pivotally mounted, at one end, a hexagonal rod B⁷, the latter being adapted to be detached when required. The two upper side faces of the hexagonal rod are so prepared 100 that graduations of any scale can be made erasable thereon by pen or pencil. The rod B⁷ carries at its pivoted end a laterally fixed pointer C⁴ to enable the reading off on the semi-circle. Another indicator C², adjustable by a set screw 7^c is slidably mounted on 105 the rod B⁷ in such a manner that the right 110

hand edge of the indicator C^2 is in line with the center of the pivot 7 and therefore adapted to mark "zero" on said rod. The indicator C^2 is slidably mounted on said rod B^7 and is so constructed that any position indicated by its lower perpendicular point C^{2a} , or any surface operated upon, is exactly indicated upon the graduations on the slides B^1 and on either side, as required, by the lateral pointers (of said indicator) C^{2b} , when the rod B^7 is moved parallelly with the edge (either side) of rule B. A set screw C^{2a} secures the indicator C^2 in any required position. A removable end supporter C^1 is mounted on the right hand end of rod B^7 , having a swiveled arm at O O and a roller at the bottom of said arm for ease of operation. A set screw C^{1a} secures said supporter in position. The right hand end of the handle B^5 is mounted on its own hollow tube, and is held by said tube on the tube of plate B^4 thus allowing the latter to revolve truly, yet freely around the spindle B^3 . The cap B^6 internally threaded, screws down, over the top of spindle B^3 , or the top of tube of plate B^4 (which is threaded for the purpose) above the tube of handle B^5 thereby keeping the latter rigid and secure in place, and also adjustably securing plate B^4 , as its pivot 7 may be required for either side of rule B. The left hand end of the handle B^5 is secured to the rule B and perfectly centered transversely near the edge of disk A^2 , by counter sunk screws. At this end of the handle B^5 are firstly a curved pointer A^7 , indicating readings on the disk A^2 . A rotating handle B^8 is removably mounted on the squared portion of spindle B^3 , above the cap B^6 and is secured thereto by set screw C^9 . A set screw C^{10} passing perpendicularly through handle B^8 , secures said handle to cap B^6 in any required position. The beveled edges of rule B are graduated, but the part below this, and beyond the bedplate A^1 is with the edges of said bedplate, square. Two small rollers B^x are fitted at the right hand end of rule B, slightly projecting below said rule, for ease of operation, Fig. 5.

50 The adjustments are effected as follows:

1. When the edges of bedplate A^1 and rule B are in line, the disk A^2 shows north and south points, or 0° transversely, and east and west, or 90° longitudinally.
- 55 2. The disk A^3 can be set to any required position and clamped by set screw A^6 .
3. The rack indicators $b b$ with their toes $b b$ and $b b^1$ meet at their inner edges, and form, when together, one continuous line with line zero on the surface and edges of rule B, and in operation by pinion and spindle B^3 , are moved equi-distant from or toward said line zero, this line zero always showing middle distance between indicators $b b$, and their toes $b b$ and $b b^1$ respectively.
- 60 4. The center

of pivot 7, when in position and ready for use, is in line, perpendicularly, with line zero on the edges of rule B on either side as required.

5. The hexagonal rod B^7 , when mounted on pivot 7, is marked zero at the right hand edge of the perpendicular indicator C^3 , and readings on said hexagonal rod are indicated by indicator C^2 , reading from zero.

The rule operates as described below, and it will be clear that the above construction may be modified provided that the essential features of the following methods of operation are retained, though the apparatus may be employed without some of the refinements.

The chart work is effected in the following manner: Having selected the chart to be used, the disk A^3 is set to the required position for variation, and clamped by set screw A^6 . The graduations from one side of the chart are transferred to slides B^1 B^1 , and a portion of the graduations from top or bottom of the chart of not less than one degree, for longitude, is transferred to the hexagon rod B^7 on the prepared surfaces thereof, the line marking the degree of graduations being placed at zero on said rod. The rule being thus equipped with the necessary elements for courses, distances, latitude and longitude for every portion of the chart is now ready for use.

To find course.—With either end of the bedplate A^1 to any convenient meridian, or either side to any convenient parallel, the rule B, by the handle B^5 is rotated and if necessary slid until either edge of said rule B is on line of position between the two given points; the pointers A^6 and A^5 will then give true and magnetic courses on disks A^2 and A^3 respectively.

To find a ship's position by cross bearings from observed objects on shore.—With the bedplate A^1 in position as given in the first example, it forms a base line from which the rule B can operate at any required position. The bearings given being magnetic and the set off given bearings with the rule B operating from the bedplate A^1 forming the base line, the point of intersection of said bearings is the position of the ship.

The question of deviation of the compass, though known well to me, I have not deemed necessary to deal with in my invention because, being a variable quantity with every position of the ship's head, it is dealt with by a "table of deviation", and can be applied easier to all magnetic bearings by such table, than by complicating my instrument with what I believe a useless addition.

To find distance from observed objects on shore.—1. If the chart is one of usual scale: The spindle B^3 is rotated until the rack indicators $b b$ are opened beyond the required distance of either of them from zero on

rule B. The slide B¹ is then moved until any parallel or round number is on said zero; zero is thereafter placed on the edge of the rule B, on point of ship's position 5 then with the hexagon rod B⁷ and its indicator C² any distance can be found, and measured, by moving said rod with the distance marked by indicator C², in parallel with rule B when said indicator will show 10 the distance on the slide B¹. In this way any number of distances can be obtained by placing the rule B north and south or east and west and with zero on ship's position, every possible bearing can be taken by hexagonal rod B⁷ around the entire circle. 2. If the chart is Mercator: With the rule B placed in position as above, move the hexagon rod B⁷ until the indicator C² rests on the nearest parallel, move said rod there- 20 after in parallel with rule B, and move slide B¹ until the corresponding parallel on its graduations comes to pointer C^{2b}; then proceed as before.

To find distance at sea, Mercator's chart.—

25 Place the rule B on line of position, and rotate spindle B³ until the toes b b and b b¹ are at the two given points respectively; then move the hexagon rod B⁷ and indicator C² until the pointer C^{2b} is on the nearest parallel; move subsequently said rod in parallel 30 with rule B, and slide B¹ until its corresponding parallel is at pointer C^{2b}. The required distance is then shown on slide B¹ between the indicator b b.

35 *In order to find latitude.*—Place zero on the edge of rule B to point to position. Move the hexagon rod B⁷ with its indicator C² until pointer C^{2b} is at the nearest parallel; then move said rod in parallel with 40 rule B, and slide B¹ until its corresponding parallel is at pointer C^{2b}, the required latitude is thus shown on slide B¹ at line zero on rule B.

In order to find longitude.—With rule B still in position as above, move the hexagon rod B⁷ and its indicator C² until pointer C^{2a} is at the nearest meridian. The result, shown 45 on the graduation of the hexagon rod B⁷ added to or subtracted from, said nearest 50 meridian, as may be required, is the longitude.

If no graduations are on the slides B¹ or

the hexagon rod B⁷, all distances and latitudes can be obtained by performing above operations on the graduated meridian on the 55 chart, while the longitude can be obtained from the top or bottom of the chart, by removing hexagon rod B⁷ from pivot 7 and applying it to the graduations on said top or bottom of the chart. 60

In applying the instrument to plans and the like, the scale required is graduated on the slide B¹ and, using the bedplate A¹ as a T-square, all straight lines of any angle can be drawn from the rule B, and all distances 65 measured by operation of racks b b with perfect accuracy.

It will be seen that by means of this combination rule the various operations can be effected with great rapidity and with perfect mathematical accuracy, under every circumstance. A simplified form of the rule, in which the racks, pinion and rod are omitted, is of great service as a rapid and accurate course adjuster. 70

Having now fully described my said invention what I claim and desire to secure by Letters Patent is:

1. A chart rule, comprising in combination a rule which is graduated at the sides, 80 two racks slidably mounted thereon, two indicators on said racks, a pinion mounted between the two racks and adapted to engage both, a pivot over the edge of the rule and at the same distance from the end of the rule 85 as the center of the pinion, a rod mounted on said pivot and being graduated at its upper face, and an indicator adapted to slide on said rod, for the purpose set forth.

2. A chart rule comprising in combination a rule, a slide on which said rule is adapted to revolve, a bed-plate upon which the slide is slidably mounted, compass cards fixed on said slide, a handle mounted above the latter, and indicators provided on said 95 handle to show the bearing of the revolving rule with respect to the compass cards.

In testimony whereof I have hereunto set my hand in the presence of two subscribing witnesses.

RICHARD TIDDY GOULD.
